CLAIM

The ornamental design for a bottom of a disc container for CD and floppy discs, as shown and described.

DESCRIPTION

FIG. 1 is an exploded perspective view of a bottom of a disc container for CD and floppy discs showing our new design, the broken lines are for illustrative purposes only and form no part of the claimed design;

FIG. 2 is a top plan view thereof;

FIG. 3 is a front elevational thereof, the rear being a mirror image;

FIG. 4 is a right side elevational view thereof, the left being a mirror image; and,

FIG. 5 is a bottom plan view thereof.
